CIRCUIT BREAKER INTERLOCK

Thomas W. Langford, Wilkinsburg, Pa., assignor
to Westinghouse Electric & Manufacturing
Company, East Pittsburgh, Pa., a corporation
of Pennsylvania

Application February 17, 1938, Serial No. 191,011

6 Claims. (Cl. 200—50)

The invention relates to enclosed circuit breakers in general, and more particularly to a safety interlocking means for the cover of the circuit breaker casing.

5 An object of the invention is the provision of an enclosed circuit breaker having a casing and an openable cover therefor with an improved interlocking means for interlocking the cover and the circuit breaker mechanism so that the cover 10 cannot be opened when the circuit breaker is in closed circuit position.

Another object of the invention is the provision of an enclosed circuit breaker having an overcenter snap acting operating mechanism and 15 a manual operating member therefor with an improved interlocking means between the cover and operating member for preventing opening of the cover when the breaker is closed, the interlocking means being effective during the full travel of 20 the operating member from closed circuit position to the point at which the mechanism automatically actuates the contacts to open position independently of any further movement of the operating member, so that the interlocking means 25 cannot be released by moving the operating member only part of the way to open position.

Another object of the invention is the provision 30 of an enclosed circuit breaker with an improved interlocking means for preventing opening of the enclosure cover when the breaker is in closed circuit position, the interlocking means being disposed in an inaccessible position entirely within the enclosure so that it cannot be released from outside the enclosure except by moving the 35 breaker operating member to open circuit position.

Another object of the invention is the provision 40 of an enclosed circuit breaker with an improved interlocking means between the enclosure cover and operating mechanism of the breaker for preventing opening of the cover when the breaker is in closed circuit position, and which permits closing of the cover when the breaker is in closed position.

45 Another object of the invention is the provision of a safety interlocking means as described above that is simple, reliable in operation and inexpensive to manufacture.

The novel features that are considered characteristic 50 of the invention are set forth in particular in the appended claims. The invention itself, however, both as to structure and operation, together with additional objects and advantages thereof will be best understood from the following detailed description of a preferred embodiment.

ment thereof when read in connection with the accompanying drawings in which:

Figure 1 is a plan view of a circuit breaker embodying the safety interlocking means of the present invention, a portion of the cover of the 5 circuit breaker enclosure being broken away.

Fig. 2 is a side elevational view partly in section, of the circuit breaker shown in Fig. 1, and

Fig. 3 is an end elevational view of the circuit breaker with a portion of the cover and casing 10 broken away to illustrate the safety interlocking means.

The interlocking means of the present invention is shown in the accompanying drawings applied to a circuit breaker which is substantially 15 identical in construction and operation to the circuit breaker disclosed in the copending application of L. Pierce and S. Miller, Serial No. 187,446, filed January 28, 1938, and assigned to the assignee of the present invention. Since the 20 structural details and operation of the circuit breaker have been completely shown and described in the above-mentioned copending application, only so much thereof is shown and described in this application as is considered necessary for a complete understanding of the present 25 invention.

Referring to the drawings, the numeral 5 designates a sheet metal enclosure formed by a substantially rectangular casing 7 and a cooperating cover 9 which is pivotally mounted on the casing 7 by a hinge means 11. The cover is releasably held in closed position on the casing by means of a pivoted spring biased latch 13 mounted on the cover 9, which engages the edge of an opening 35 provided in an end wall of the casing 7.

A multipole circuit breaker unit carried by a base 15 is mounted within the enclosure 5. The circuit breaker unit comprises in general a plurality of pairs of spaced stationary contacts 17, 40 a plurality of cooperating movable bridging contact members 19 for forming a plurality of poles, and an operating mechanism indicated generally at 21 for operating the movable bridging contact members 19.

The movable bridging contact members 19 are mounted in transverse spaced relation on a cross arm 23 of insulating material which is secured intermediate its ends to the outer end of a switch member 25. The switch member 25 is mounted 50 for linear rolling movement on a U-shaped frame 27 by means of a roller 29 which extends transversely between the side walls of the frame 27.

The operating mechanism 21 is carried by the frame 27 between the side walls thereof and in- 55

cludes a releasable carrier 31 pivoted at 33 in the frame 27. A pair of actuating links 35 are pivoted at their upper ends by means of a pivot pin 37 on the carrier 31 and have their lower ends 5 pivotally connected by means of a pivot pin 39 to the inner end of the movable switch member 25. A U-shaped operating member 41 is pivotally mounted on a pair of lugs 43 struck outwardly from the side walls of the frame 27 and is connected to the inner end of the movable switch member 25 by a pair of overcenter springs 45, which have their upper ends connected to the bight portion of the operating member 41 and their lower ends connected to the pivot pin 39 which connects the actuating links 35 to the switch member 25. The upper end of the operating member 41 has an insulating operating handle 47 secured thereto which projects through an elongated opening 49 provided in a well 51 formed in the cover 9. The operating member 41 is also provided with an arcuate shield 53 which serves to close the opening 49 in all positions of the operating member, and with a depending projection 55 which serves to reset the mechanism following a tripping operation.

The releasable carrier 31 is biased in a clockwise direction about its pivot axis 33 by the overcenter springs 45 and is releasably held in a normal latched position by a main latch member 57 which is pivoted on the frame 27 by a pivot pin 59, the carrier 31 being provided with a rounded latch nose 61 which normally engages the upper edge of an opening 63 provided in the main latch 57. The main latch 57 is in turn releasably held in its latched position, against the releasing force transmitted thereto by the overcenter springs 45, by means of a second latch 65 which is pivoted on the main frame 27 by means of a pin 67. The second latch 65 is biased in a clockwise direction by a helical spring 69 interposed 40 between the latch 65 and the base of the frame 27, and the latch 65 is held against movement beyond the latching position as shown in Fig. 2 by an inwardly bent projection 71 formed in the end of the main latch 57.

A pair of current responsive release units indicated generally at 73 (Fig. 1) are detachably mounted on opposite sides of the main frame 27 and each includes a snap acting bimetal disk 50 and a heater coil (not shown) which are mounted within an insulating block 75. The heater coils of the two current responsive release units 73 are connected in series circuit with the contact means of the two outer poles of the breaker by 55 a pair of flexible shunt conductors 77 so as to be heated in response to the current flowing in the outer poles of the breaker. The bimetal disk of each current responsive release device 73, when heated a predetermined amount in response to 60 an overload in the circuit of its pole, moves with a snap action from its original position to an inverted position and acts through an insulating button 79 and a trip lever 81 which extend through the side wall of the frame 27 to effect downward 65 or counterclockwise movement of the second latch 65 to trip the circuit breaker to open position. When the bimetal disc is cooled below a predetermined temperature following a tripping operation it returns to its original position.

The operation of the circuit breaker as thus far described is briefly as follows:

To manually open the circuit breaker the operating member 41 is moved by the handle 47 in a counterclockwise direction about its pivot axis 43 from the closed position shown in Fig. 2 to

the open position adjacent the opposite end of the elongated opening 49. This movement of the operating member 41 moves the line of action of the overcenter springs 45 towards the left as viewed in Fig. 2. When the operating member reaches the position indicated by the dotted lines in Fig. 2, the line of action of the overcenter springs 45 has been carried across the axis of the pivot pin 37 which connects the upper ends of the actuating links 35 to the carrier 31, and the force exerted by the overcenter springs moves the switch member 23 and the movable bridging contacts 19 carried thereby to open circuit position with a snap action independently of any further movement of the operating member 41. The force exerted by the overcenter springs also acts to carry the operating member 41 onto its full open circuit position.

To close the circuit breaker the operating member 41 is moved by the handle 47 in a clockwise direction about its pivot axis 43 from the open circuit position to the closed circuit position shown in Fig. 2. At a certain point in the closing movement of the operating member, the line of action of the overcenter springs 45 moves to the right 25 of the pivot pin 37 following which the force exerted by the springs moves the switch member 25 and the bridging contact members 19 carried thereby to closed position with a snap action. The operating member 41 is also moved onto the full 30 closed circuit position by the force exerted by the overcenter springs. It will thus be seen that no matter how slowly the operating member is moved to operate the circuit breaker, the switch member 25 and movable contacts are always moved 35 with a snap action after the operating member has been moved a predetermined amount in either direction.

If an overload of predetermined magnitude and duration occurs in the circuits of either of the 40 outer poles of the breaker the bimetal disk of the current responsive release unit 73 of the affected pole moves to its inverted position to effect release of the latches 57 and 65, and the carrier 31. When the carrier is thus released in response 45 to an overload, it is moved in a clockwise direction about its pivot axis by the overcenter springs 45. The clockwise movement of the carrier 31, following its release, carries the pivot pin 37 to the right of the line of action of the overcenter springs 50 45, and the overcenter springs then move the switch member 25 to a tripped open circuit position and the operating member 41 and handle 47 to an intermediate tripped indicating position.

Before the circuit breaker can be reclosed following a tripping operation as described above, it is necessary to reset the carrier 31 and the latches 57 and 65. To reset the mechanism, the operating member 41 is moved in a counterclockwise direction about its pivot axis 43 toward open 55 position. During this resetting movement of the operating member, the depending projection 55 thereof engages and moves the carrier 31 in a counterclockwise direction. The carrier 31 is moved in a counterclockwise direction slightly 60 beyond the latched position shown in Fig. 2 to effect resetting of the main latch 57 and the second latch 65. When the carrier 31 returns to its latched position after latches 57 and 65 have been 65 reset, the latch nose 61 thereof is reengaged under 70 the edge of the opening 63 in the main latch member 57. The mechanism is now completely reset and the circuit breaker may be reclosed in the manner previously described.

A novel safety means is provided for inter- 75

locking the cover 9 of the enclosure 5 to prevent opening thereof whenever the circuit breaker is in its closed circuit position. The interlocking means comprises a lateral projection 83 formed integral with the operating member 41 by being struck out from the upper end of one of the legs of the operating member, and a cooperating springclip 85 which is secured to the inside of the cover 9, either by welding or by mechanical means, and positioned at the side of the well 51 and elongated opening 49 thereof. The lower end of the clip 85 is angularly bent back as shown in Fig. 3 to provide a hooked end 87 (Fig. 3), and the clip 85 is so disposed that the hooked end lies in interlocking relation under the lateral projection 83 of the operating member 41 when the operating member 41 is in and adjacent to its closed circuit position as shown in Fig. 2, thus preventing opening of the cover 9 when the circuit breaker is in closed circuit position.

As will be seen in Fig. 1, the clip 85 is of a width such that the left hand edge thereof is disposed directly above the axis of the pivot pin 37 which supports the actuating links 35, thus rendering the interlocking means effective to interlock the cover 9 during the full travel of the operating member 41 from closed position to the position at which the operating mechanism 21 continues its movement automatically to open the circuit breaker independently of any further opening movement of the operating member 41. The last mentioned critical intermediate position of the operating member 41 is indicated by the dotted lines in Fig. 2 and it will be noted that in this position the lateral projection 83 of the operating member 41 has just cleared the hook end 87 of the spring clip 85. Thus it will be seen that it is impossible to release the cover by pushing the operating handle 47 only part of the way to open circuit position. To release the interlocking means to permit opening of the cover 9, it is necessary to move the operating handle 47 a sufficient distance in the opening direction to cause the mechanism 21 to effect opening of the contacts of the breaker.

The angularly bent hook end 87 of the clip 85 provides an inclined cam surface, and this together with the inherent resiliency of the clip 85 allows it to flex and clear the projection 83 on the operating member 41 when the cover 9 is closed with the operating member 41 in closed circuit position. This eliminates the possibility of damage to any parts of the circuit breaker in case the cover should be slammed shut when the operating member 41 is in the "on" or closed circuit position.

It will be noted that the entire interlocking means comprising the lateral projection 83 and the spring clip 85 is disposed in an inaccessible position entirely within the enclosure 5, where it cannot be manipulated to effect release of the cover when the operating member 41 is in closed circuit position.

While the invention has been disclosed in accordance with the provisions of the patent statutes, it is to be understood that various changes in the structural details thereof may be made without departing from the spirit of the invention. It is desired, therefore, that the appended claims be given the broadest reasonable interpretation permissible in view of the prior art.

I claim as my invention:

1. In an enclosed electrical switch, an enclosure having an openable cover, an electrical switch

mounted within said enclosure having an operating member operable from outside said enclosure, said cover and said operating member being provided one with a projection and the other with a spring clip, both of which are disposed within the enclosure, for interlocking the cover to prevent opening thereof when the switch is in closed circuit position.

2. In an enclosed circuit breaker, an enclosure having an openable cover, a circuit breaker having an operating mechanism mounted within the enclosure, said operating mechanism being operable from outside said enclosure, said cover and a movable actuating element of the operating mechanism being provided one with a projection and the other with a spring clip, both of which are disposed within the enclosure for interlocking the cover to prevent opening thereof when the circuit breaker is in closed circuit position.

3. In an enclosed circuit breaker, an enclosure having an openable cover, a circuit breaker mounted within said enclosure having an operating mechanism including a movable operating member that is operable from outside said enclosure, interlocking means disposed entirely within said enclosure for interlocking the cover to prevent opening thereof when the circuit breaker is in closed circuit position comprising a lateral projection carried by said movable operating member within the enclosure and a hook shaped spring clip secured to the inside of the cover in a position such that it is disposed in interlocking relation relative to the projection on the operating member when the operating member is in and adjacent to its closed position.

4. In an enclosed circuit breaker, an enclosure having an openable cover, a circuit breaker mounted within said enclosure having an operating mechanism including a movable operating member that is operable from outside said enclosure, in combination, interlocking means for the cover for preventing opening thereof when the breaker is in closed circuit position comprising a lateral projection carried by the operating member within the enclosure, and a spring clip secured to the inside of the cover having a hooked end which underlies the lateral projection of the operating member when the operating member is in and adjacent its closed circuit position.

5. In an enclosed circuit breaker, an enclosure having an openable cover, a circuit breaker mounted within said enclosure having an over-center spring operating mechanism including a movable operating member that is operable from outside the enclosure, in combination, interlocking means disposed entirely within the enclosure for interlocking the cover to prevent opening thereof when the circuit breaker is in closed circuit position comprising a lateral projection carried by the operating member within the enclosure and a spring clip secured to the inside of the cover having a hook end which is disposed in interlocking relation under the lateral projection when the operating member is in closed position, said projection and clip being of a width to prevent opening of the cover during substantially the full travel of the operating member from its closed position to the position at which the operating mechanism automatically moves to the open position independently of any further movement of the operating member.

6. In an enclosed circuit breaker, an enclosure having an openable cover, a circuit breaker

mounted within said enclosure having an operating mechanism including a movable operating member that is operable from outside said enclosure, in combination, interlocking means for the cover for preventing opening thereof when the breaker is in closed circuit position comprising a lateral projection carried by the operating member within the enclosure, and a spring clip secured to the inside of the cover having a hooked

end which underlies the lateral projection of the operating member when the operating member is in and adjacent to its closed circuit position, the resiliency of said clip permitting the hooked end thereof to clear said projection during closing of the cover when the operating member is in closed position. 5

THOMAS W. LANGFORD.
